UNITED STATES PATENT OFFICE.

WILLIAM JAMES FISH, OF ROUSEVILLE, PENNSYLVANIA.

INJECTOR.

Application filed December 22, 1921. Serial No. 524,280.

To all whom it may concern:

Be it known that I, WILLIAM J. FISH, a citizen of the United States, and a resident of Rouseville, in the county of Venango and State of Pennsylvania, have invented 5 certain new and useful Improvements in Injectors, of which the following is a specification.

My invention relates to injectors or spraying devices for use in connection with oil 10 engines.

Devices of this type are adapted to be screwed into an oil engine and the fuel oil is supplied to the cylinder through the injector or spraying device. The purpose of 15 these injectors is to spray or feed the oil into the engine cylinder in a finely comminuted condition.

In general my invention relates to injectors of this general type and has for its 20 particular object to provide a simple durable and efficient construction and furthermore, one wherein the working parts of the injector will be somewhat protected from the force of the explosions occurring in the 25 engine cylinder.

Another feature of my invention resides 20 in the provision of a removable valve seat and means for adjusting the tension applied to the valve.

My invention consists essentially in a plug or casing threaded at both ends to enable it to be attached to the fuel pump and engine cylinder respectively and provided with a 35 spraying point, a slotted stand, a valve member and a spring interposed between said slotted member and stand.

The operation of my improved invention and the features of construction thereof will 40 be made more apparent in the accompanying specification and drawings, in which:

Fig. 1 is a fragmentary sectional view of 45 an engine cylinder with my invention applied thereto,

Fig. 2 is an enlarged longitudinal section of the injector,

Fig. 3 is an elevation of the outer end of the injector,

Fig. 4 is an elevation of the inner end of the injector, and

Fig. 5 is a perspective view of a detail thereof.

In the drawings wherein like numerals refer to like parts, the numeral 10 indicates 55 a plug-like casing or housing threaded at one end thereof as indicated at 11 to enable

it to be screwed into a combustion chamber or the like, such as the head of an engine cylinder 12 as illustrated in Fig. 1 of the drawings. Injectors when employed in connection with oil engines are connected to the cylinder of the engine in such a manner as to spray oil onto a hot plate or the like but inasmuch as this forms no part of my present invention, further detailed description 60 thereof is believed unnecessary.

The other end of the plug-like casing which will hereafter be termed the outer end, is screw-threaded as indicated at 13 to enable it to be connected to the fuel supply pipe 14 usually in turn, connected to a pump. Such connection may be accomplished in any known manner but I have here shown a coupling sleeve 15 as the means of connecting the outer end of the casing 65 10 to the fuel supply pipe 14.

The casing 10 is squared as indicated at 16 for the reception of a tool whereby the casing 10 may be conveniently screwed into the wall of the engine cylinder and as is 70 plainly obvious from the drawing, the threaded portion 11 is tapered to insure a leak-proof joint at this point.

The casing 10 is bored centrally and internally screw-threaded at one end thereof 75 for the reception of an externally screw-threaded valve seat plug 17, which valve seat plug is bored centrally as indicated at 18. The outer end of the plug 17 is slotted as indicated at 19 for the accommodation of 80 a tool whereby the seat plug may be screwed into the outer end of the casing 10.

Cooperating with the valve plug is a valve formed with a reduced stem 20, a shank 21 and an enlarged central portion 22. The 85 stem 20 is connected to the enlarged central portion 22 by a beveled surface 23 and the diameter of the shank 21 is somewhat reduced so as to form a shoulder 24 against which one end of a spring 25 abuts. The beveled portion 23 of the valve seats upon 90 the inner end of the valve plug 17 as clearly illustrated in Fig. 2. The distance which the plug 17 may be screwed into the casing 10 is limited by an inner shoulder 26 formed 95 on the inside of the casing 10.

The inner end of the casing 10 is provided with internal screw-threads for the reception of an externally threaded nozzle or plug 27, provided with a beveled collar 28 which seats in a corresponding recess formed 100 in the end of the casing 10 and provided 110

further with a squared projection 29. The plug is in the form of a sleeve-like member, providing a central passage 30 while the squared portion 29 is pierced by a restricted opening 31 through which the oil is forced into the engine cylinder.

Interposed between the said plug 27 and the spring 25 is a spindle or stand 32, shown more in detail in Fig. 5. The end of the 10 stand 32 adjacent the valve is recessed as at 33 so as to loosely receive the end of the shank 21. The stand is provided with tapered cut-out portions 34 diametrically opposite one another, the deepest part of each cut-out portion being disposed adjacent the recess 33, communication being established between these cut-out portions and the recess 33 by apertures 35. Commencing at the ends of the cut-out portions 34 and extending to 20 the other end of the stand 32 is a pair of diametrically disposed slots 36, the depth of which tapers toward the inner end of the stand 32, where they meet, providing the stand 32 with a bifurcated end 37. The 25 bifurcated end of the stand 32 abuts the spray plug 27, thereby enabling the stand 32 to be axially displaced by screwing inwardly on the plug 27.

As is clearly illustrated in Fig. 2, the 30 spring 25 abuts with one of its ends against the shoulder 24 formed on the valve member, while the other end of the spring lies against the outer end of the stand 32. Obviously a displacement in an outward direction of the 35 stand 32 increases the tension of the spring 25 and hence, causes the valve member to seat more firmly against the inner end of the valve plug 17.

In practice, the device is screwed into the 40 cylinder of an engine and the outer end connected to the fuel supply from which fuel is obtained under pressure, usually by a pump. The oil enters the casing through the opening 18 in the valve plug and the pressure thereof unseats the valve whereupon the fuel is forced through the valve casing, during its course passing through the recess 33, openings 35, cutout portions 34 and slots 36 in the stand 32, thence through the center 45 of the spray plug and through restricted opening 31 into the engine cylinder, where it is directed against the usual hot plate. When an explosion occurs the back pressure is borne mostly by the stand 32, thus protecting the spring 25 and the valve from 50 disastrous shocks. Because of the bifurcated end 37 and the longitudinally extending slots 36, the force of explosion is divided and passed backwardly toward the valve 55 through the tapered slots 36, which as will be noted, taper in a direction to retard the force of the explosion. These explosive gases must therefore pass through the restricted points where the cut-out portions 60 34 and the slots 36 join and must thereafter

furthermore pass through the restricted openings 35. Thus it will be seen that the force of the explosion coming back into the casing is dissipated considerably and no undue strains are exerted upon the valve or 70 its associated spring. However, the force of the explosion which reaches the valve, augmented by the pressure of the spring 25 will be sufficient to seat the valve momentarily so as to prevent the passage of the 75 explosive gases back into the fuel supply pipe.

As hereinbefore stated, the valve plug 17 is removable and may be replaced when the same becomes worn or otherwise mutilated. 80 The tension on the spring 25 which regulates the pressure with which the valve seats may be varied by proper rotation of the spray plug 27, which affects the spring through the stand 32. Obviously this may be easily 85 accomplished because of the squared end 29 formed in this manner to accommodate the tool required for rotating the said plug.

As will be seen, the number of parts required in my improved construction are few 90 in number and are so formed that they may be made durable and manufactured cheaply. However, my improved construction is conducive of the desired results in devices of 95 this type in that the fuel is supplied to the engine cylinder in a spray as is necessary in this type of engine and liability of exhaust gases being forced into the fuel supply is guarded against.

While I have shown and illustrated one 100 form of my invention, I do not wish to be unnecessarily limited but reserve the right to make such changes and modifications as may come within the purview of the accompanying claims.

Having thus described my invention, what I claim is:

1. In a device of the class described a 110 housing adapted to be inserted in the wall of an engine cylinder, means for supplying fuel to said housing, a valve, a spray plug and a stand interposed between said valve and said spray plug and provided with continuous tapering slots to dissipate the back pressure through said housing.

2. In a device of the class described a 120 plug-like casing adapted to be screwed into the wall of an engine cylinder, said casing being hollow, means for supplying fuel under pressure to said casing, a displaceable valve contained within said casing, a spray plug in the other end of said casing and a stand interposed between said valve and said plug, said stand being formed with restricting passageways forming wedge-shaped obstructions to dissipate the back pressure through said casing.

3. In an injector of the class described, a 130 casing threaded at one end thereof to enable it to be screwed into the wall of an engine

cylinder, means at the other end of said casing for connecting it to a source of fuel supply, said casing being hollow, a valve and valve seat in said casing, spring means for causing said valve to seat, a spray plug in the other end of said casing and a stand interposed between said plug and said spring, said stand being formed with a pair of tapering grooves forming a wedge-shaped obstruction, as and for the purpose described.

4. In an injector of the class described a plug-like hollow casing screw-threaded at both ends whereby it may be screwed into the wall of an engine cylinder and connected to a source of fuel supply, a removable valve plug formed with a seat secured in one end of said casing, a valve contained within said casing and seating on said plug, a spring associated with said valve for causing said valve to seat, a spray plug removably secured in the other end of said casing and a spindle-shaped stand contained within said casing and bearing with its ends against said spray plug and said spring respectively, whereby the tension of said spring may be regulated by rotating said spray plug.

5. In a device of the class described a plug-shaped hollow housing, said housing being threaded externally at both ends 30 thereof to enable the same to be screwed into the wall of an engine cylinder and connected to a fuel supply pipe, a threaded valve plug removably secured in one end of said casing and providing a valve seat, a displaceable 35 valve within said casing, a spring associated with said valve and causing said valve to seat upon said plug, a removable spray plug secured in the other end of said casing, said plug being provided with a squared end 40 and a spindle-like stand contained within said housing and bearing with its ends against said plug and said spring, said stand being formed at one end with a recess for the reception of the adjacent end of the 45 valve, a pair of diametrically disposed tapered cut-out portions and a pair of diametrically disposed tapering slots, said slots meeting at the other end of said stand, forming a bifurcated end therefor and providing 50 a tortuous passage through which the fuel passes on its way through said housing.

WILLIAM JAMES FISH.
